UNITED STATES PATENT OFFICE.

WILLIAM MILLWARD, OF PITTSBURGH, PENNSYLVANIA.

REGENERATIVE FURNACE.

Application filed July 5, 1923. Serial No. 649,501.

Heretofore, it has been usual in furnace operations to introduce the gas at such velocities as may be established by the pressure on the producer, the extent to which the gas inlet valve is opened, and the pull of the stack. The amount of air supplied and the velocity thereof depends on the regulation of the air inlet valve, the temperature of the regenerator, and the pull of the stack. The operation was regarded a success if the air overtook and burned the gas before it reached the end of the furnace. Otherwise stated, little or no importance was attached to securing proper admixture of the air and gases as a condition precedent to ultimate combustion.

The principal object of my invention is to provide for sharp combustion, thereby shortening the furnace operation and increasing the efficiency of the furnace. I attain this result, without regard to the source and character of the gas, by a systematized boosting and dilution of the gas with appropriate supplies of air, and by effecting the mixing of the air and gas in stages. In short, the essence of my invention resides in effecting primary and secondary mixing of the air and gas, and to some extent it depends on an unobstructed or free passage for the air rising from the regenerator system.

With such and other objects in view, the nature, characteristic features and scope of the invention will more readily be understood from the following description taken in connection with the accompanying drawings, forming a part hereof, wherein—

Figure 1 is a sectional view of an open hearth furnace of the regenerative type, showing principally the gas and air uptakes from the slag pockets and the means for effecting stage mixing and for boosting the velocity.

Fig. 2 is a transverse section.

Referring to the drawings, it will be manifest to those skilled in the art that fuel for the furnace 1 is essentially supplied, as is usual, from the slag pockets of the regenerators, the gas rising in the uptake 2 and the air rising in the uptake 3. The gas uptake 2 is provided with a gooseneck terminal 4, the nose or delivery portion of which is equipped with a water jacket 5. A blast nozzle 6 projects into the gooseneck and supplies air under proper control to dilute the gas and to boost the velocity thereof. The nozzle

is so disposed with relation to the outlet of the gooseneck, that the upper or horizontal arm of the latter constitutes a primary mixing chamber *a*, wherein air is mixed with gas coming from the checkerwork. The gooseneck 4 does not overhang or extend into the air uptake 3, but discharges its mixture across a gap into a secondary mixing chamber *b*, wherein further mixing takes place with the air rising untrammelled in the free and unobstructed air passage 3. As shown in Fig. 2, the delivery or outlet portion of the gooseneck and the element 7, forming the mixing chamber *b*, are preferably, but not essentially, oval in cross-section. The merit of the oval shape is that it ensures a comparatively wide and shallow flame. Whatever cross-section is employed it is important that the blast nozzle, gooseneck terminal, and secondary mixing chamber be relatively centered, and that the intake of the secondary mixing chamber be substantially flared as at 8.

While I have merely illustrated and referred to essentials of the invention, it will be understood that atmospheric air is supplied to the gooseneck in the direction of the flow of gas and at any desired pressure and that the gas is thus boosted to that velocity necessary to induce the air in the air uptake into the secondary mixing chamber. The velocity may be governed by the size of the nozzle. The point of desired combustion with a given gas depends upon the degree to which the gas is diluted with oxygen in the primary mixing chamber, the prompt admixture with this mixture of the air rising in the air uptake, and of course the temperature of all. Combustion may be delayed somewhat by drawing waste gases from the outgoing regenerator, mixed with atmospheric air to cool them, into the blower so that the air blast will contain less oxygen, and the amount of oxygen may also be regulated by the temperature of the air blast. Manifestly, the flame in the furnace may be made as short or as long as desired by the speed of the blower and by the use of the usual regulating valves for gas and air inlets. If desired, as in heating furnaces, to effect complete combustion directly the fuel enters the hearth, the flame is so shortened as to be practically invisible, but for melting purposes this of course is not practical as the melting is best accomplished by the cutting action of the flame and the latter must have body to cut the metal. The rate of

transmission of heat from the gas to the metal by convection increases with the velocity of the gas flame.

Having described my invention, I claim:—

- 5 1. Means for effecting sharp combustion in furnaces of the regenerative type, comprising the combination with the gas and air uptakes, of a primary mixing chamber in the outlet end of the gas uptake, means for supplying 10 air thereto for boosting and diluting purposes, and a secondary mixing chamber in line with the first and spaced therefrom by the air uptake.
- 15 2. Means for effecting sharp combustion in furnaces of the regenerative type, comprising the combination of a gas uptake having an outlet arm, a mixing chamber in said outlet arm, means for diluting the gas and for boosting the velocity thereof with regulated supplies of air, a secondary mixing chamber, 20 and a free and unobstructed air uptake separating said mixing chambers.
3. Means for effecting sharp combustion in furnaces of the regenerative type, comprising the combination of a gas uptake, an unobstructed air uptake, a gooseneck terminal 25 for the gas uptake and stopping short of the air uptake and constituting a primary mixing chamber, means for supplying it with air under pressure, a secondary mixing chamber centered relatively to the first and to said means, and a system of control.

In testimony whereof I affix my signature.
WILLIAM MILLWARD.
